UNITED STATES PATENT OFFICE.

SAMUEL G. GREEN, OF THE UNITED STATES ARMY.

ELECTRICALLY-CONTROLLED MECHANISM FOR FIREARMS.

1,352,891.

Specification of Letters Patent. Patented Sept. 14, 1920.

Application filed July 2, 1919. Serial No. 308,300.

(FILED UNDER THE ACT OF MARCH 3, 1883. 23 STAT. L., 625.)

To all whom it may concern:

Be it known that I, SAMUEL G. GREEN, Lieutenant, Ordnance Department, U. S. A., a citizen of the United States, stationed at 5 Washington, D. C., have invented an Improvement in Electrically-Controlled Mechanism for Firearms, of which the following is a specification.

The invention described herein may be 10 used by the Government, or any of its officers or employees in prosecution of work for the Government, or by any other person in the United States, without payment of any royalty thereon.

15 While this invention relates generally to firearms, it has more particular reference to machine guns, and is directly concerned with the problem of firing such guns from a distance, so that the operator may occupy 20 a position of safety removed from proximity to the gun and fire the same with the same facility as if he were actually beside the gun, with his finger on the trigger thereof.

The fundamental object of the invention, 25 therefore, is to solve the problem of firing a firearm, such as a machine gun, from a distance.

A further object is to provide electrically 30 controlled mechanism for firing the gun from a distance.

Another object is to provide a form of mechanism for accomplishing the result noted which will be very simple in construction, thoroughly reliable and positive in operation, and susceptible of manufacture at 35 a low cost.

The accompanying drawings disclose one 40 of the number of possible physical embodiments of the underlying principles of the invention. The drawings, therefore, show merely an exemplary construction. Like reference characters indicate corresponding parts throughout the several views. Briefly described:

45 Figure 1 is a view in side elevation of the form of embodiment which I have selected to illustrate the underlying principles of the invention;

Fig. 2 is a top plan view thereof;

50 Fig. 3 is a central vertical sectional view through the electro-magnet;

Fig. 4 is a transverse sectional view on the line 4—4 of Fig. 1; and

Fig. 5 is a diagram of the electrical circuit.

55

Referring, now, in detail to the drawings:

The form of the invention shown in the drawings is designed for use in connection with a type of machine gun in which the 60 trigger is tilted upward to fire the gun. It will be understood that, when used with other types of machine guns having, for instance, a trigger which is pulled rearward instead of being tilted, the mechanism shown 65 in the drawings will be slightly changed so as to adapt it for use with such guns, such change being readily made by any skilled mechanic.

1 designates the tubular portion of handle-block carrying the depending handle 2.

3 designates the trigger, which is pivoted, so that, in firing, it is tilted upward on its pivot.

4 designates a cradle or saddle, which may 75 be made of sheet metal. The saddle carries bearings 5, 5 in which are journaled the pivot-pin 6 of a screw 7, passing through an opening 8 in a strap 9 carried by the cradle 4. A wing-nut 10 threaded on the 80 screw 7 and against the strap 9 frictionally clamps the saddle on the tubular portion 1 of the handle-block.

The cradle carries, at its rear end, depending legs 11, 11 provided with segmental angular portions 12, 12 carrying, at their ends, flanges 13, 13, through which passes a threaded bolt 14 carrying a nut 15, whereby the segmental members 12, 12 may be frictionally clamped around a tubular housing 90 85 16 for an electro-magnet 17. A threaded bolt 18 may pass through the legs 11, 11 and be provided with a nut 19 so that the cradle 4, at its rear end, may be contracted to frictionally bind the same on the tubular member 1 of the handle-block. The housing 16 is threaded laterally for engagement with threaded caps or covers 20, 20 closing the ends of the housing. The top cover carries the binding posts 21, 21 for the terminals 100 of electrical conductors 22, 22 of the electric circuit, shown in Fig. 5.

Fulcrumed on the pin 23 carried by the bracket 24 supported from the saddle 4 is a bell crank lever 25, the shorter arm 26 of 105 which is pivoted on a pin 27 carried by a

trigger-engaging member 28, which is bent at its lower end, as shown at 29, so as to extend beneath the trigger 3, the end of said bent portion being turned upward to provide the upstanding member 30. Preferably, a plate 31 is disposed on the bent portion 29 so as to extend transversely thereof, and the ends of this plate are bent upward, as shown at 32, 32. The lower end of the trigger 3 is thus inclosed on all sides by the lower end of the member 28 and the plate 32. The free end of the longer arm of the lever 25 is bifurcated, as shown at 33, to provide ears 34, 34 embracing the upper end 15 of the link 35 pivoted at its lower end, as shown at 36, to the armature 37 of the magnet. A pivot-pin 38 passes through the ears 34, 34 and through the upper end of the link 35. Between the fulcrum point of 20 the lever 25 and the rear end thereof is a coil spring 39, bearing, at one end, against the under surface of the lever 25 and at its other end, against the top of the saddle 4. The spring normally maintains the lever 25 and armature in raised position, as is obvious.

In operation, when the switch 40 is moved to close the circuit, the electro-magnet 17 will be energized, thereby attracting the 30 armature 37, which moves downward, rocking the lever 35 so as to pull the trigger-engaging member 28 upward, thus tilting the trigger 3 and firing the gun.

It will be understood that the electro- 35 magnets of a number of machine guns constituting a battery may be connected up in

series, so that all of the machine guns in the battery may be fired simultaneously by one operator through the operation of a single switch.

Having described my invention, what I claim as new and desire to secure by Letters Patent, is:—

1. The combination with a firearm, of a saddle adapted to be secured thereto, an electro-magnet supported by said saddle and having an armature, a trigger-engaging member, a lever for moving said trigger-engaging member and actuated by the armature of said magnet, and an electric circuit including said magnet. 40

2. The combination with a firearm, of a saddle adapted to be secured thereto and having complemental segmental members, an electro magnet having an armature and 55 provided with a housing embraced by said segmental members, a trigger-engaging member, a lever for moving said trigger-engaging membr connected to the armature, and an electric circuit including said magnet. 60

3. The combination with a firearm, of a saddle, means for frictionally securing the saddle to the firearm, an electro-magnet having an armature and provided with a housing, means for frictionally securing said 65 housing to said saddle, a trigger-engaging member, a lever for moving said trigger-engaging member and actuated by the armature of said magnet, and an electric circuit including said magnet.

SAMUEL G. GREEN.
